(57) **CLAIM**

The ornamental design for a multi-chambered package, as shown and described.

DESCRIPTION

FIG. 1 is a top perspective view of a multi-chambered package of the present invention showing our new design;

FIG. 2 is a bottom perspective view thereof;

FIG. 3 is a top plan view thereof;

FIG. 4 is a bottom plan view thereof;

FIG. 5 is a side elevational view thereof; and,

FIG. 6 is a further side elevational view thereof, the multi-chambered package being rotated relative to the side view in FIG. 5.

The broken lines shown herein depict environmental subject matter only and form no part of the claimed design.

1 Claim, 6 Drawing Sheets(56)
